DESIGN FOR A TUMBLING APPARATUS

George E. Huenerfauth, Park Ridge, Ill., assignor
to Crown Rheostat & Supply Co., Chicago, Ill.,
a corporation of Illinois

Application March 31, 1944, Serial No. 113,097

Term of patent 14 years

(Cl. D55—1)

To all whom it may concern:

Be it known that I, George E. Huenerfauth, a citizen of the United States, residing at Park Ridge, in the county of Cook and State of Illinois, have invented a new, original, and ornamental Design for a Tumbling Apparatus, of which the following is a specification, reference being had to the accompanying drawing, forming part thereof, in which—

Fig. 1 is a side elevational view of a tumbling apparatus showing my new design;

Fig. 2 is a plan view of the tumbling apparatus; and

Fig. 3 is an end view of the tumbling apparatus.

I claim:

The ornamental design for a tumbling apparatus, substantially as shown.

GEORGE E. HUENERFAUTH.
